(57) **CLAIM**

I claim the ornamental design for a profile surface of a hood for a barbecue grill, as shown and described.

DESCRIPTION

FIG. 1 is a perspective view of a profile surface of a hood for a barbecue grill showing our new design; and, FIG. 2 is a side elevational view thereof.

The details shown in broken lines in both views are for illustrative purposes only and form no part of the claimed design.

The portions of the barbecue hood not shown in the drawings or described in the specification form no part of the claimed design.
